(57) **CLAIM**

The ornamental design for a leaf for blinds, as shown and described.

DESCRIPTION

FIG. 1 is a perspective view of a leaf for blinds, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The break lines shown in FIGS. 1-3 and 6-7 symbolize breaks in the length of the article in which the claimed design is embodied. The appearance of any portion of the article between the break lines that forms no part of the claimed design.

1 Claim, 7 Drawing Sheets
